ROTARY PUMP AND MOTOR.

1,079,384.

Specification of Letters Patent.

Patented Nov. 25, 1913.

Application filed September 26, 1912. Serial No. 722,487.

To all whom it may concern:

Be it known that I, JAMES MAXWELL WILSON, of the city of Toronto, county of York, in the Province of Ontario, Canada, have invented certain new and useful Improvements in Rotary Pumps and Motors, of which the following is a specification.

This invention relates to rotary pumps and motors and has for its object to provide a machine adapted to be used either as a motor or as a pump in which the direction in which the rotors rotate may be reversed and the speed of said rotors varied while the flow of the driving fluid is maintained in the same direction; or in the case of a machine used as a pump a variable quantity of fluid may be delivered in either direction with the rotors running at any constant speed in any one direction.

20 A further object is to provide for the balancing of the internal and external pressure upon vane chamber of the machine whereby the bursting effort on said vane chamber is reduced to a minimum and a still further object is to provide means for balancing the lateral pressure upon the rotor and bearings for the purpose of reducing friction and consequent wear upon said bearings and to increase the general efficiency of the machine.

A still further object is to provide for the resilient pressing outward of the vanes so that they will automatically take up any wear either in themselves or in the interior 35 of the vane chamber.

To attain these objects I construct my rotary motor or pump with an outer casing or housing having suitable bearings therein in which the rotor and its shaft may be journaled, and an inner casing or vane chamber which surrounds the rotor and is adapted to be moved perpendicularly to the axis of said rotor whereby the cylindrical bore of said vane chamber may be adjusted 45 in its eccentricity on either side of the said rotor. The inlet and outlet ports of the vane chamber are provided with short tubular members extending therefrom and movable longitudinally in cylindrical openings in the outer casing, the joint between the tubular members and the outer casing being provided with U shaped washers which will allow of the escape of fluid between the said tubular members and the outer casing, to the exterior of the vane chamber and so

balance the internal and external pressure thereon. In the outer casing, both above and below the rotor bearings, are provided semi-annular channels which are independent of each other and each of which has a duct or hole communicating with the space between the opposite side of the rotor and the vane chamber so that pressure upon one or other side of the rotor when the machine is in operation will be transmitted by means of said ducts to the opposite side of the bearings thereby relieving the lateral pressure upon the casing or housing, which would otherwise produce great friction and result in the consequent material loss of efficiency of the machine. The rotor, as is usual, carries the vanes which are capable of movement in a plane radial to the axis of the said rotor and their inner ends bear upon plain or frusto-conical roller or rollers, the faces of the said inner ends, where frusto-conical rollers are used being suitably inclined so that they may conform to the conical surface of the said roller or rollers. The arrangement is more fully described and illustrated in the following description and the drawings in which:

Figure 1 is a sectional elevation of a hydraulic rotary machine constructed according to my invention. Fig. 2 is a transverse section through the vane chamber of the same. Fig. 3 is an end view of the inlet and exhaust ports and Fig. 4 is a sectional detail view showing the vanes and their supporting rollers.

Similar characters of reference indicate similar parts in the several figures of the drawings.

1 is the outer casing or housing of the machine, constructed in any suitable manner and number of parts to facilitate the assembling of the same; and 2 is the inner casing or vane chamber slidable within the said outer casing or housing.

Arranged axially within the outer casing 100 1 is the rotor 3 which consists of two parts 4 and 5 connected together end to end by suitable screw bolts 6 or the like, the whole being rotatably supported by the ball bearings 7 and also journaled in the annular plain bearings 8 8 in the outer casing 1. A shaft 9 is connected to the rotor and extends axially therefrom through the end of the machine, endwise thrust upon the said shaft 9 being taken up by the ball thrust bearing 110

10 which abuts against an adjusting ring 11. Leakage of fluid from the machine along the surface of said shaft 9 is prevented by means of a stuffing box 12 which may be 5 of any suitable construction. The rotor 3 is radially slotted to accommodate the vanes 13 the outer ends of which are retained in contact with the inner cylindrical surface of the vane chamber 2 at what- 10 ever position the said vane chamber may be in with respect to the rotor 3.

The vane chamber 2 is provided with inlet port 14 and outlet port 15 the openings of which are coincident with the suction and 15 delivery openings 16 and 17 in the outer housing or casing of the machine, connection being established between the ports in the vane chamber and the openings 16 and 17 in the outer casing, by means of short 20 tubular members 18 and 19 fixed to said vane chamber 2 and slidable in the said openings 16 and 17. It will be understood that either of the said ports 14 or 15 may form the inlet or the outlet port of the 25 machine according to the direction in which it is desired that the fluid shall flow, or, in the case where the machine is used as a pump, the direction in which the fluid is driven, but for purposes of clearness the port 14 will herein be referred to as the 30 inlet port.

The fluid pressure within these machines is often very high and a strong bursting effort is exerted upon the inner walls of the 35 vane chamber 2 which I reduce by allowing the fluid under pressure to gain access to the outer walls of the said vane chamber 2 and so balance the internal stress thereon. This is accomplished by means of annular 40 grooves in the outer casing 1 around the tubular members 18 and 19 in which are accommodated leather U shaped packing rings 20 with their concave faces disposed toward the vane chamber 2. The function 45 of these packing rings 20 is to allow of the passage of fluid under pressure between the tubular members 18, 19 and the walls of the openings 16, 17 to the space surrounding the vane chamber 2 and to prevent leakage 50 from the vane chamber to either one of the openings 16 or 17 in which the pressure may be lower than in the vane chamber.

The vane chamber 2 is capable of a lateral movement with respect to the axis of 55 the rotor 3 which is effected by means of an operating rod 21 passing through the outer casing, means, such as a U shaped packing ring, being provided to prevent leakage at this point. Grooves 22 are provided at the 60 top and bottom of the vane chamber 2 to allow the fluid surrounding the same to pass from one side of the outer casing to the other when the said vane chamber is moved. The lateral movement of the vane chamber 65 2 brings the same to an eccentric position

on the side nearest to or farthest removed from the inlet and exhaust ports, according to the direction in which the said vane chamber is moved, the intermediate position being that in which the rotor and the 70 vane chamber are concentric. Thus the lateral movement of the vane chamber 2 will allow the hydraulic fluid to pass through the said chamber on either the near or far side of the rotor.

The vanes 13 carried by the rotor 3 are supported by oppositely disposed frusto-conical rollers 23, carried by a spindle 24 upon which one of said rollers 23 is slidable and pressed toward the other roller by a 80 coiled spring 25 or equivalent resilient means. The inner ends of the vanes 13 are inclined toward the center to conform with the conical sides of the said rollers 23 in such manner that the tendency of the spring 25 to press the rollers 23 together forces the said vanes 13 outwardly and so keeps their outer edges in contact with the inner cylindrical surface of the vane chamber 2.

One or more floating rollers may be used 90 if desired to form a bearing surface for the inner edges of the vanes, but this would, of course, only be applicable where more than two vanes were used, and the said rollers may be either plain or conical as desired, 95 resilient means being provided in the case of a conical roller or rollers to hold the same against correspondingly inclined inner faces of the vanes.

It will be seen that as the rotor 3 rotates, 100 the vane chamber being in an eccentric position thereto, the vanes 13 will oscillate radially with respect to the rotor axis while moving in a circular path with the said rotor 3.

In operation, assuming that the machine is being used as a motor with the parts in the positions shown in the drawings and fluid under pressure is entered by the port 14, the said fluid will occupy the space between the ends of the vanes 13. This will cause the said vanes to move around and rotate the rotor, the fluid passing in the same direction down that side of the vane chamber farthest removed from the inlet port 14 and passing out through the port 15. By altering the eccentricity of the vane chamber 2 with respect to the rotor 3 in the manner already described, the space between the rotor and that side of the vane chamber referred to, may be decreased while at the same time a corresponding increase in the space between the rotor and the other side of the vane chamber takes place which decreases the pressure upon the descending 115 vanes while a certain proportion of the pressure is exerted against the ascending vanes which results in the slower rotation of the said rotor. When the rotor and vane chamber are concentric the pressure upon the 120 125 130

vanes at each side of the rotor is balanced and no rotation can take place, but it will be obvious that the further movement of the vane chamber in the same direction will 5 result in the rotation of the rotor in the reverse direction owing to the fact that the pressure would then be greater on the vanes nearest to the inlet than on the other vanes. The direction and speed of rotation of the 10 rotor can therefore be governed without altering the pressure or direction of flow of the fluid.

The machine may be used as a pump by mechanically or otherwise rotating the rotor, the vanes then performing the function of driving the hydraulic fluid either up one side or down the other side of the vane chamber according to the position of the vane chamber 2 with respect to the said rotor 3, the direction of flow of the fluid being reversed or the delivery of the same controlled without altering the speed or direction of rotation of the said rotor 3. Ordinarily the pressure upon the rotor would 25 be exerted upon that side of the same disposed toward the inlet, where the machine is used as a motor, and upon the discharge side where the machine is used as a pump, and this would result in great friction and 30 wear in the bearings and consequently loss of efficiency in the machine. To overcome this objection I provide means whereby hydraulic pressure may be transmitted from the part in which the pressure exists to the 35 opposite side of the rotor, whereby the said pressure is balanced about the axis of the rotor. This is accomplished by providing upper and lower semi-annular channels 26 and 27 respectively in each of the annular 40 plain bearings 8. 8 of the casing and connecting the upper channels 26 with the lower port 15 by means of ducts or holes 28 and the lower channels 27 with the upper port 14 by ducts 29. Should the fluid pressure be 45 in the upper port 14 the said pressure will be transmitted along the ducts 29 to the semi-annular channels 27 in the bearings 8 and so counteract the lateral pressure upon the rotor 3, the said ducts and channels being, of course, filled with the fluid.

Hydraulic or gaseous fluid may be used in this machine according to requirements or oil may be used with advantage in which case the oil would also serve to lubricate 55 the parts and would insure a smooth working of the machine.

In a machine of this type the use of valves, gearing or other undesirable mechanical complications for providing for the reversing or controlling of the machine is obviated. Further vibration in the machine is 60 minimized owing to the constant velocity of the hydraulic fluid and the speed or direction of the fluid or of the rotor can be controlled from zero to maximum, perfectly

graduated, without steps. The balancing of the pressures both on the interior and exterior of the vane chamber and upon opposite sides of the rotor insures the highest efficiency in the machine with minimum 70 amount of friction.

This invention may be developed within the scope of the following claims without departing from the essential features of the same and it is desired that the specification 75 and drawings be read as being merely illustrative and not in a limiting sense except as necessitated by the prior art.

What I claim as my invention is:—

1. In a rotary machine the combination of 80 an outer casing; a rotor revoluble within said casing; vanes movably mounted in radial slots in said rotor; a vane chamber surrounding said rotor; oppositely disposed frusto-conical rollers upon which correspondingly inclined inner edges of said vanes bear; and resilient means tending to force the two rollers together.

2. In a rotary machine the combination of 90 an outer casing; a rotor revoluble within said casing; a vane chamber surrounding said rotor, laterally movable in said casing and provided with inlet and outlet ports; means for admitting fluid pressure from the interior to the exterior of said vane chamber, in communication with each port; said means preventing fluid pressure passing in the reverse direction.

3. In a rotary machine the combination of 100 an outer casing; a rotor revoluble within said casing; a vane chamber surrounding said rotor laterally movable in said outer casing; inlet and outlet ports to said vane chamber, tubular members connecting said ports with openings in the outer casings 105 and slidably therewithin; and U shaped washers between said tubular members and said casing adapted to allow fluid under pressure to gain access to the exterior of said vane chamber to balance the internal pressure.

4. In a rotary machine the combination of 115 an outer casing; a rotor revoluble within said casing; a vane chamber surrounding said rotor, laterally movable in said outer casing; inlet and outlet ports in said vane chamber; tubular members connected therewith and slidably in openings in said outer casing; U shaped washers around said tubular members adapted to allow fluid under 120 pressure to gain access to the exterior of said vane chamber; and means for allowing the movement of fluid from one part of the outer casing to another around said vane chamber when it is moved laterally.

5. In a rotary machine the combination of 125 an outer casing; a rotor revoluble within said casing; a vane chamber surrounding said rotor, laterally movable in said outer casing; inlet and outlet ports in said vane 130

- chamber; tubular members connected therewith and slideable in openings in said outer casing; U shaped washers around said tubular members adapted to allow fluid under pressure to gain access to the exterior of said vane chamber; and grooves at the top and bottom of said vane chamber to allow of the passage of the fluid from one part of the casing to another when the vane chamber is moved laterally.
6. In a rotary machine the combination of an outer casing; a rotor revoluble in said casing; bearings in the outer casing supporting said rotor; a vane chamber movable in said outer casing, surrounding said rotor; upper and lower ports in said vane chamber; semi-annular channels above and below each of said bearings, independent one of the other; and ducts forming communication between said channels and the port on the opposite side of the rotor thereto.
7. In a rotary machine the combination of an outer casing; a rotor revoluble in said casing; bearings in said outer casing supporting the rotor; a vane chamber laterally movable in said outer casing surrounding said rotor; upper and lower ports in said vane chamber; upper and lower semi-annular grooves in said bearings each in communication with the port on the opposite side of the rotor; and means for distributing fluid pressure to the exterior of the vane chamber.
8. In a rotary machine the combination of an outer casing; a rotor revoluble therein; bearings supporting the rotor; a laterally movable vane chamber surrounding said rotor; upper and lower ports in said vane chamber; corresponding openings in the outer casing; upper and lower semi-annular grooves in said bearings each in communication with the port on the opposite side of the rotor; tubular members connected with the ports, slideable in said corresponding openings; and U shaped washers surrounding said tubular members so positioned that fluid may gain access to the exterior of the vane chamber.
9. In a rotary machine the combination of an outer casing; a rotor revoluble in said casing; more than two vanes mounted in radial slots in said rotor; the said vanes having inclined inner faces; a vane chamber surrounding said rotor, movable with respect thereto; and connected and oppositely disposed frusto-conical rollers upon which the correspondingly inclined inner faces of said vanes bear.
10. In a rotary machine the combination of an outer casing; a rotor revoluble in said casing; more than two vanes mounted in radial slots in said rotor; the said vanes having inclined inner faces; a vane chamber surrounding said rotor, movable with respect thereto; and connected and oppositely disposed frusto-conical rollers upon which the correspondingly inclined inner faces of said vanes bear and means for adjusting said rollers toward one another.
11. In a rotary machine the combination of an outer casing; a rotor revoluble in said casing; more than two vanes mounted in radial slots in said rotor, the said vanes having inclined inner faces; a vane chamber surrounding said rotor, movable with respect thereto; oppositely disposed frusto-conical rollers upon which the said correspondingly inclined inner faces of said vanes bear; a spindle attached to one of said rollers, the other roller being slideable thereon, and a spring upon said spindle tending to force the slideable roller toward the fixed roller.
12. In a rotary machine the combination of an outer casing; a rotor revoluble within said casing; vanes movably mounted in radial slots in said rotor, said vanes having inclined inner faces; a vane chamber surrounding said rotor and adapted to be moved to a position on either side of said rotor; oppositely disposed frusto-conical rollers upon which the said correspondingly inclined inner faces of said vanes bear; a spindle attached to one of said rollers, the other roller being slideable thereon; and a spring upon said spindle tending to force the slideable roller toward the fixed roller.

Toronto, this 3rd day of September 1912.
JAMES M. WILSON.
